UNITED STATES PATENT OFFICE.

BERTRAM J. GOLDSMITH, OF NEW YORK, N. Y., ASSIGNOR, BY MESNE ASSIGNMENTS,
TO PERFECT WINDOW REGULATOR CORPORATION, OF LONG ISLAND CITY, NEW
YORK, A CORPORATION OF DELAWARE.

DOOR HANDLE.

Application filed July 25, 1924. Serial No. 728,083.

My invention has for its object the production of a handle for vehicle or other doors or for any closure member which shall be of simple construction and easily and cheaply manufactured.

A further object of the invention is the production of a handle of the character specified which shall be made of sheet metal so formed or shaped as to produce a walled structure having an open side, this walled structure receiving a filler member on to which the free and continuous edge of the wall is bent to hold the filler member in position.

Further objects of the invention will appear from the accompanying description, the invention consisting in the novel handle hereinafter described and then specified in the claims.

In the accompanying drawing illustrating a practical embodiment of the invention:

Fig. 1 is a front elevation of a door showing my improved handle applied thereto.

Fig. 2 is a section taken through the handle showing one stage in its manufacture.

Fig. 3 is a horizontal section on the line 4—4 of Fig. 4.

Fig. 4 is a view similar to Fig. 2 but showing the handle after its completion.

Fig. 5 is a front elevation of the handle.

Fig. 6 is a vertical cross-section on the line 6—6 of Fig. 4.

Referring to the several figures of the drawing:

1 indicates the base of the outer shell of the handle which is formed of sheet metal and 2 indicates an upstanding continuous four sided wall which is integral with said base whereby a rectangular-shaped hollow sheet metal structure having an open side is produced. 3 indicates a hollow squared bearing which is also integral with the base 1 and which extends outwardly therefrom. Said bearing 3 is adapted to receive a squared shaft or shank 4 therein, said shaft being provided with a head 5 whereby outward withdrawal of said shaft from said bearing is prevented. The shaft 4 is adapted to be connected in any manner with any suitable latch or bolt (not shown) so that when the handle is manually rotated the latch or bolt will be actuated.

For reinforcing the walls of the handle

and for the purpose of enhancing the appearance of the device I have provided a 55 filler member 6 of a size permitting it to be snugly received within the walled structure described. The filler member is preferably formed of a substance which is relatively light and strong and may with satisfaction be formed of hard black rubber. Said filler member 6 is provided with a recess 7 extending completely around the edge of the four sides thereof. For clamping or holding said filler member in position I preferably 60 bend the edges 8 of the four sides of the upstanding continuous wall 2 downwardly at right angles to the wall 2 and into the recess 7 as indicated at 8 in Figs. 4, 5 and 6 whereby said bent edges will lie in the same 65 plane as the upper surface of the filler member. By using black hard rubber as the filler instead for instance, cement, lightness, in weight of the handle is secured while at the same time a firm support for the walls 70 is provided. The parts also may be easily assembled and the finished handle has an ornamental appearance as the color of the rubber contrasts sharply with that of the 75 metal.

By the construction described I have produced a handle which may be very inexpensively manufactured and which is neat in appearance. It will be noted also that the bent portions of the sheet metal are rounded 80 whereby all sharp corners are eliminated.

What I claim as my invention is:

1. A rectangularly-shaped sheet metal handle having an open side, a filler member comprising a removable and separately 90 molded and hardened block in said handle and held in position therein by a portion of said handle bent over into engagement therewith and means associated with said handle for receiving a connecting member. 95

2. A sheet metal handle comprising a base and a four-sided wall integral therewith, a hollow squared bearing also integral with said base, a squared shaft held within said bearing and provided with a head adapted 100 to prevent said shaft from being withdrawn outwardly from said bearing and a filler member enclosed by said wall.

3. A sheet metal handle comprising a base, a four-sided wall integral therewith and extending outwardly therefrom, a filler mem- 105

ber comprising a removable and separately molded hardened block of rubber snugly received within said wall and held in position by bending over the free edge of said wall on to said filler member whereby a substantial part of a surface of said filler member is exposed to view and means associated with

said handle for receiving a connecting member.

Signed at New York in the county of ¹ New York and State of New York this 24th day of July, A. D. 1924.

BERTRAM J. GOLDSMITH.
